UNITED STATES PATENT OFFICE.

HUGO FRITZSCHE, OF LEIPSIC-GOHLIS, GERMANY.

PHOTOGRAPHER'S DISH OR TRAY.

SPECIFICATION forming part of Letters Patent No. 781,510, dated January 31, 1905.

Application filed August 26, 1904. Serial No. 222,342.

To all whom it may concern:

Be it known that I, HUGO FRITZSCHE, manufacturer, a subject of the German Emperor, and a resident of Fechnerstrasse 4, in the city 5 of Leipsic-Gohlis, Germany, have invented new and useful Improvements in Photographers' Dishes or Trays, of which the following is a specification.

This invention relates to water-tight dishes 10 or trays for photographers' use, which are preferably made in two sizes, one adapted to slip within the other, and when so made they may be assembled in pairs and used as boxes in which photographic plates, films, paper, and 15 the like may be placed for sale.

More particularly, the invention relates to such dishes or trays made of some peculiarly inexpensive material, as cardboard or the like, which being permeable must therefore be 20 treated for water-tightness. As the trays when used for plate-boxes are preferably made with the containing-walls at right angles to the bottom and of such size that the plates fit snugly therein, some device must be used to 25 enable the photographer to readily lift the plates off the bottom of the tray when developing.

The objects of the invention, therefore, are to provide means for effecting the results as 30 above stated; and to the accomplishment of these objects and such others as may herein-after appear the invention comprises the novel construction and combinations of parts hereinafter described, and particularly pointed out 35 in the appended claims, reference being had to the accompanying drawings, forming a part hereof, in which the same reference characters designate like parts throughout the several views, in which—

40 Figure 1 shows the improved photographers' developing-tray with a plate lying therein. Fig. 2 shows the tray of Fig. 1 with the plate lifted into position for ready removal; and Fig. 3 shows a similar tray to that shown by 45 Fig. 1, but slightly larger and adapted to fit over the former.

Referring to the drawings, *a* is the material used for the body of the tray, which is coated with varnish or impregnated with resin or 50 other varnish-like substance capable of ren-

dering the permeable material forming the body water-tight, as shown at *b*. A tape or band *e* is secured at one end to the inner side of the bottom of the tray, as at *c*, the tape being made of such length that when laid 55 snugly across the bottom and up one side the other end will extend beyond the edge. Resting within the tray and on this band *e* is a plate or film *f*, which, as is readily seen, fits snugly within the sides of the tray, which are 60 preferably perpendicular to the bottom. The usefulness of this tape *e* is obvious and is illustrated by Fig. 2. Without it or some equivalent means it would be necessary to reverse the tray to get out the plate; but by pulling 65 on the projecting end of the tape, and thereby extending it, the plate is brought into a position where it can be easily grasped by the fingers. The band *e* may be made of any convenient material, as rubber or paraffined 70 strands, strips, cord, &c.; but it must be of some material not affected to any great extent by dampness or by the baths used for photographers' purposes.

It is readily seen that by the construction 75 as above described a tray for photographers' use is provided which is so inexpensive that it may conveniently be used in combination with a second one of slightly larger size as a 80 box for plates, films, paper, &c., and, in fact, is much stronger and more durable than an ordinary cardboard box, owing to the inside coating of varnish, and at the same time the varnish or impregnating substance can be selected so as to make the material used for the 85 body of the box not only water-tight, but protect the contents from the influence of light, electricity, and the like.

Preferably the trays are pressed out of a single blank of cardboard, so as to avoid any 90 seams or joints, which considerably increases the tray's strength.

It is not desired to be understood that the invention is limited to the exact details of construction and arrangement of parts as herein 95 described and illustrated, as it is manifest that numerous variations and modifications may be made in the features of construction and arrangement and in the adaptation of the device to various conditions of use without de- 100

parting from the spirit and scope of the invention and improvements. The right is therefore reserved to all such variations and modifications as properly fall within the scope of 5 the invention and the terms of the following claims.

I claim—

1. The combination with a photographer's tray of permeable material made water-tight, 10 having perpendicular containing-walls and a bottom substantially the size of the plate to be developed, of means for withdrawing the plate from the tray without reversal, substantially as described.
- 15 2. The combination with a photographer's tray of permeable material made water-tight, having perpendicular containing-walls and a bottom substantially the size of the plate to be developed, of an extensible band having a 20 portion secured to the tray-bottom and another portion projecting beyond the edge of the tray for withdrawing a plate therefrom without reversal, substantially as described.
- 25 3. The combination with a cardboard photographer's tray made water-tight, having perpendicular containing-walls and a bottom substantially the size of the plate to be developed, of an extensible band attached to the 30 tray for withdrawing a plate therefrom without reversal, substantially as described.
- 35 4. The combination with a cardboard photographer's tray coated on the inside with an enameling varnish, having perpendicular con-

taining-walls and a bottom substantially the size of the plate to be developed, of an extensible band attached to the bottom of the tray for withdrawing a plate therefrom without reversal, substantially as described. 35

5. A pair of photographers' developing-trays constructed and coöoperating the one to 40 fit within the other to be used as a receptacle for undeveloped plates, each of said trays being formed of permeable material made water-tight having perpendicular containing-walls of such dimensions as to fit snugly about a 45 plate to be developed and provided with means for withdrawing a plate without reversing the tray, substantially as described.

6. A pair of cardboard developing-trays made water-tight, constructed and coöperating the one to fit within the other to be used as a receptacle for undeveloped plates, each having perpendicular containing-walls of such dimensions as to fit snugly about a plate 50 to be developed and each provided with an extensible band attached to its bottom for withdrawing a plate without reversing the tray, substantially as described. 55

In testimony whereof I have signed my name to this specification in the presence of two sub- 60 scribing witnesses.

HUGO FRITZSCHE.
